MEANS FOR PREVENTING SHIFTING OF LOADS IN RAILWAY CARS AND THE LIKE

Filed Sept. 8, 1930

Fig. 1.

UNITED STATES PATENT OFFICE

JAMES B. CHALMERS, OF GARY, INDIANA, ASSIGNOR TO THE YOUNGSTOWN SHEET AND TUBE COMPANY, OF YOUNGSTOWN, OHIO, A CORPORATION OF OHIO

MEANS FOR PREVENTING SHIFTING OF LOADS IN RAILWAY CARS AND THE LIKE

Application filed September 8, 1930. Serial No. 480,370.

In the shipment of certain classes of goods in railway cars and the like it is necessary to very firmly brace the goods after they are loaded into the car to prevent their shifting about therein when the car is in motion. Such bracing is required by the railroad authorities and is also obviously necessary to prevent damage to the goods and to the car, particularly when the former are of relatively heavy nature.

My invention therefore relates to the art of bracing loads of goods under these conditions and while it may desirably be utilized in connection with numerous sorts and classes of articles, it is particularly applicable to the bracing of loads consisting of a plurality of similar relatively heavy packages such, for example, as packages of tin plates or metallic sheets of comparatively small size and I shall therefore herein refer more especially to the employment of the invention for that purpose.

Tin plates or metal sheets of the class to which I have referred are ordinarily prepared for shipment by piling the sheets one upon another until a bundle about eighteen inches high is formed and then binding the sheets together into a unit with wire or the like, a platform of wood or the like being frequently placed beneath the bottom sheet and bound into the package. At other times the sheets are placed in suitable wooden boxes which are nailed up or bound with wire preparatory to shipment.

These packages of sheets or the boxes containing the latter are then placed side by side in rows on the floor of the car in the opposite ends thereof, adjacent packages being usually separated by suitable means such as strips of wood or the like, a passage or space extending across the center of the car being left vacant. The group of packages at either end of the car is usually then bound together as an integral whole with wires extending both longitudinally and transversely of the

car. In the passage or space adjacent the center of the car between the groups some form of transverse bracing means bearing in opposite directions against the opposed inner ends of the groups of packages is then placed in position and timbers cut to the proper lengths and usually of two inch by four inch cross-section disposed longitudinally of the car and in engagement with the transverse braces with a view to preventing longitudinal shifting of the loads in the opposite ends of the car.

It has been my experience with load braces of the class just described that excessive amounts of lumber and of labor in bracing the load are required, and furthermore, that the movement of the car during transit frequently causes the load to shift with such force as to snap the longitudinal timbers just referred to, which are thus rendered useless to thereafter retain the load in its proper position in the car, whereby damage to the load and to the car often results from further shifting.

Other forms of load bracing means have also been devised comprising, for example, metal turn buckles disposed longitudinally of the car and bearing against retaining means engaging the ends of the groups of packages, but these as well as all other means with which I am familiar and which are satisfactorily effective to prevent the shifting of the load require either some such relatively expensive form of apparatus or such a large amount of time and material in their construction that their cost is substantially prohibitive.

It is therefore among the purposes and objects of my invention to provide bracing means particularly adapted for use in association with railway box cars of the usual type employed for making shipments of the character to which I have referred and which may be relatively easily and quickly erected in the car after the loading thereof, which re-

quire no great amount of skill or labor for their erection and which are satisfactorily effective to prevent the shifting of the load in the car while the latter is in transit.

5 A further object of my invention is to provide bracing means of the class described which require but a relatively small amount of lumber or other material for their construction with consequent lowering of the 10 cost thereof to the shipper.

10 Other purposes, objects and advantages of my invention will hereinafter be more specifically mentioned or will appear from the following description of a preferred embodiment thereof as employed in association with a railway box car loaded with tin plate, reference being had to the accompanying drawings.

15 While my invention is particularly adapted to employment in railway cars and more especially in box cars of the usual type, it will be understood that it is equally applicable to railway cars of other types, to motor trucks, steamships or the like and in fact to many 20 other situations in which it is desired to provide a strong and secure brace satisfactorily effective to prevent the shifting of a load.

25 Inasmuch as a fully loaded box car braced for transport in accordance with my invention is substantially symmetrical with respect to its transverse median line, I shall hereinafter particularly describe the arrangement of the various elements employed on one side only of this line, and it will thus be readily comprehended that the description applies generally with equal force to the arrangement at the other side of said line.

30 In the said drawings, Fig. 1 is a fragmentary horizontal section of a box car loaded as described, the plane of section being above the top of the load; Fig. 2 is a vertical fragmentary section on the line 2—2 in Fig. 1 and Fig. 3 is a perspective view of a single bundle of sheets in which one manner of securing them together to form an individual package is clearly shown. Like characters of reference are used to indicate the same parts in the several figures.

35 Referring now more particularly to the drawings, the box car 1 as usual is provided with central door openings 2 and is loaded with a plurality of packages 3 disposed on the floor at opposite ends of the car and extending nearly to the doors thereof. It will be understood that the packages 3 each comprises a plurality of sheets which may be disposed on a small platform 4 and bound thereto by the wires 5 surrounding the entire package, corner protectors 6 being employed to 40 prevent the wire cutting the edges of the upper sheets in the package. Between adjacent packages and extending to the floor of the car I provide, during the loading of the car, vertically disposed strips of wood 8 which prevent contact between adjacent packages of

70 sheets and also near the end of the car similar vertically disposed strips 9 and a wide board 10 extending transversely of the car and resting on the floor thereof. At the opposite end of the group of packages, that is the end adjacent the doors of the car, I also provide laterally spaced vertical strips 11 and a horizontally extending retaining bar 12, comprising a plurality of relatively heavy timbers 12' secured together, the bar being notched 75 at the centers of its opposite ends for a purpose which will hereinafter appear. Extending longitudinally of the car at laterally spaced intervals and surrounding the retaining board 10 and the retaining bar 12, I arrange a plurality of wires 14 and bind the group of packages together therewith longitudinally. Between the sides of the car and the group of packages I further provide 80 boards 16 and bind the group of packages together transversely by a plurality of wires 17.

85 I also preferably secure to each side wall of the car adjacent the door and relatively near the floor as shown a horizontally extending bar 18 which is preferably nailed in place and against which a wedge 19 can bear when inserted between the bar 18 and the adjacent end of the transverse retaining bar 12, the wedges engaging the retaining bar in the notches hereinabove referred to. When 90 the car has been loaded and the packages tied with the wires 14 and 17 as described, the wedges are driven home, thereby forcing the retaining bar tightly against the group of packages, after which both wedges are nailed to the horizontal bars 18 by nails 20 and suitable strips 22, cut to the proper length, are disposed at each side of the car between the opposed ends of the wedges in order to lock the latter in place against horizontal movement, the said strips being nailed to the horizontal bars, as by nails 23, in order to securely hold them in place.

95 As will be understood from the above description, after the wedges are driven tightly home, the retaining bars are securely maintained against their respective groups of packages and any movement of the car tending to force the latter toward the center of the car will further tighten the retaining bars against the wedges at their opposite ends and render movement of the packages still more difficult. I thus eliminate any excessive compression strains on longitudinally extending timbers which might be snapped thereby for 100 in accordance with my invention such strains are taken up substantially entirely by the wedges and the retaining bars and operate merely to increase the firmness with which the retaining bars, and in turn the load, are held. Furthermore, by placing the wedges near the floor of the car no appreciable bulging effect 105 upon the walls of the car is produced, so that possible damage to the car is avoided.

110 It will thus be apparent that I have pro- 115

vided means for bracing a load of the class described which requires but relatively little effort to erect, which is satisfactorily operative to retain the load in position in the car, which needs but a comparatively small amount of material for construction and may be installed relatively quickly. Moreover, no great skill is required to satisfactorily brace a load in accordance with my invention and uniform parts are employed throughout except for the longitudinal strips 22 holding the wedges in place, which may be of greater or less length depending on the distance between the wedges, and, of course, the operation of sawing the strips to the proper length is a very simple one.

Thus my invention affords many advantages over the braces heretofore employed in that not only is it more effective since the firmness with which the load is held in position is increased as the stresses exerted against the braces increase, but also a minimum amount of material and but a relatively short time is required for installation after the car is fully loaded. Consequently the expense involved in bracing the car load for transit in accordance with my invention is materially reduced below that incident to the employment of the forms of bracing heretofore generally utilized.

It will be understood that while I have shown and particularly described a preferred form of the invention as it may be applied to a box car, many modifications in the structure and arrangement of the several parts will readily occur to those skilled in the art and may be made without departing from the spirit and scope of the appended claims.

Having thus described my invention, I claim and desire to protect by Letters Patent of the United States:

1. In combination with a railway car or the like having a load of material disposed on its floor adjacent each end thereof, retaining means disposed transversely of the car and respectively engaging said loads, a pair of wedges respectively disposed between one end of each of said retaining means and the adjacent wall of the car operative to maintain said engagement of the retaining means, and locking means operative to prevent displacement of the wedges.

2. In combination with a railway car or the like having a load of material disposed on its floor adjacent each end thereof, retaining means disposed transversely of the car and respectively engaging said loads, a pair of oppositely extending wedges respectively disposed between one end of each of said retaining means and the adjacent wall of the car and operative to maintain said engagement of the retaining means, and locking means disposed between and in operative engagement with both of said wedges.

3. In combination with a railway car and

the like having a load of material disposed on its floor adjacent one end thereof, retaining means engaging said load transversely of the car, wedges respectively extending between the ends of said retaining means and the adjacent walls of the car, and locking means engaging each of said wedges operative to retain it in wedging position.

4. In combination with a railway car or the like having loads of material disposed in opposite ends thereof, bracing means for said loads comprising a retaining bar engaging each of said loads and having a notch in each of its ends, a wedge engaged in each of said notches, a bar disposed between each of said wedges and the adjacent wall of the car and extending longitudinally thereof, a plurality of locking means respectively adapted to extend between each pair of longitudinally aligned wedges, and means for securing each of said locking means to the adjacent longitudinally extending bar, whereby each of said loads of material is braced against the other through said bracing means.

5. The combination with a railway car or the like having a load of material disposed at each end thereof, of means for preventing shifting of said loads comprising transversely extending members respectively abutting the adjacent ends of the loads, wedging means interposed between the several ends of said members and the adjacent sides of the car and means interposed between the adjacent ends of said wedging means on each side of the car operative to maintain said wedging means in predetermined spaced relation.

6. The combination with a railway car or the like having a load of material disposed at each end thereof, of means for preventing shifting of said loads comprising transversely extending members respectively abutting the adjacent ends of the loads, a wedge interposed between each end of each of said members and the adjacent side of the car, the wedges adjacent each load extending in the opposite direction from those adjacent the other load, and means interposed between the oppositely directed wedges adjacent each side of the car operative to maintain said wedges in predetermined spaced relation.

7. A load brace for a railway car having piled material disposed in opposite ends thereof comprising a pair of bars disposed transversely of the car and respectively bearing against the piles of material, a wedge disposed between each end of each of said bars and the adjacent wall of the car, and a plurality of locking means disposed substantially longitudinally of said car and each engaging a pair of oppositely directed wedges.

8. A load brace for a railway car comprising wedges operative to bear against the walls of the car, transversely extending bars engaged by said wedges and operative to prevent displacement of the load in the car and

locking means operative to prevent displacement of the wedges.

9. A load brace for a railway car comprising a wedge operative to bear against a wall of the car, a transversely extending bar engaged by said wedge and operative to prevent displacement of the load in the car, and means operative to prevent displacement of the wedge.

10. In witness whereof I have hereunto set my hand this 3rd day of September, 1930.

JAMES B. CHALMERS.
